[57] CLAIM

The ornamental design for a toy construction piece, as shown and described.

DESCRIPTION

FIG. 1 is a perspective view of a toy construction piece in an exploded condition, showing my new design.

FIG. 2 is a top plan view thereof;

FIG. 3 is a front elevational view thereof;

FIG. 4 is a right side elevational view thereof;

FIG. 5 is a front elevational view of the right side element of FIG. 1;

FIG. 6 is a left side elevational view thereof;

FIG. 7 is a cross-sectional view thereof taken along line A—A in FIG. 5;

FIG. 8 is a bottom plan view thereof;

FIG. 9 is a front elevational view of the left side element shown in FIG. 1;

FIG. 10 is a right side elevational view thereof;

FIG. 11 is a cross-sectional view thereof taken along line B—B in FIG. 9; and

FIG. 12 is a bottom plan view thereof.
